(57) CLAIM

The ornamental design for a shelf divider for merchandize displays, as shown and described.

DESCRIPTION

FIG. 1 is a side elevational view of a shelf divider for merchandize displays according to the invention.

FIG. 2 is a top plan view thereof.

FIG. 3 is an end elevational view thereof.

FIG. 4 is an end elevational view thereof from the opposite end.

FIG. 5 is a highly enlarged view of a lower portion thereof at one end, there being a mirror image thereof at the opposite end; and,

FIG. 6 is a bottom plan view of the portion thereof shown in FIG. 5.

1 Claim, 2 Drawing Sheets

FIG. 2

FIG. 1

FIG. 3

FIG. 4

FIG. 5

FIG. 6
